UNITED STATES PATENT OFFICE.

WILLIAM L. PHELAN, OF NEW YORK, N. Y.

DESIGN FOR A WALL-CABINET.

50,209.

Specification for Design.

Patented Jan. 16, 1917.

Application filed November 21, 1916. Serial No. 132,704. Term of patent 14 years.

To all whom it may concern:

Be it known that I, WILLIAM L. PHELAN, a citizen of the United States, residing at New York, in the county of Bronx and State of New York, have invented a new, original, and ornamental Design for Wall-Cabinets, of which the following is a specification, reference being had to the accompanying drawing, forming part hereof.

The figure is a perspective of the wall cabinet, showing my new design.

I claim:

The ornamental design for a wall cabinet, as shown.

WILLIAM L. PHELAN.
